UNITED STATES PATENT OFFICE.

GERHARD IMMAND, OF ESSEN, GERMANY, ASSIGNOR TO FRIED. KRUPP AKTIEN-
GESELLSCHAFT, OF ESSEN-ON-THE-RUHR, GERMANY.

DUMPING CAR.

Application filed October 14, 1921. Serial No. 507,688.

To all whom it may concern:

Be it known that I, GERHARD IMMAND, residing at Essen, Germany, a citizen of the German Republic, have invented a certain 5 new and useful Improvement in Dumping Cars, of which the following is a specification.

This invention relates to dumping cars and has for its object to enable the car to 10 be loaded and unloaded as a normal non-dumping car.

An embodiment of the invention is disclosed by way of example in the accompanying drawings in which

15 Fig. 1 illustrates a side view of the car in question, and

Fig. 2 illustrates an end view of the same.

It will be seen that both sides of the car 20 are formed by two flaps A and B and a double door C the halves of which are vertically journaled on said flaps A B. The flap A is swingingly mounted at its upper edge to uprights D and E by means of bolts 25 d^1 and e^1 whereas the flap B is similarly mounted by means of bolts f^1 and g^1 to the uprights F and G. This type of side wall support enables the space above the double door C to remain free and, as the flaps A B 30 together with the door C hinged thereto, are disposed in front of the uprights D, E, F, G, it enables further a swinging movement of the entire system comprising the two flaps A B and the door C, when the car is 35 being tilted for unloading.

As a consequence of the free space above the door C the car can be readily loaded or unloaded by means of hand trucks for example through the open doors C. Moreover by the same reason it is equally possible to load or unload the car by crane throughout without having to raise the loads above the top edge of the car.

The manner of using the car as a dumping car needs no further explanation.

I claim:

1. A dumping car having horizontally hinged side flaps suspended from their upper edge and a door in each side flap journaled on the latter.

2. A dumping car having horizontally hinged side flaps and a door in each side flap journaled vertically on the latter.

3. A dumping car having side flaps suspended from their upper edge, means for horizontally hinging said side flaps at their upper edge, a door in each side flap journaled vertically on the latter, said hinging means extending only above the portions of said side flaps lying at the side of said door, thus leaving free the space above the door.

4. A dumping car having a bottom, a plurality of uprights mounted on said bottom, side flaps, means establishing horizontal hinged connection of the upper edge of said side flaps with said uprights, a door in each side flap journaled vertically on the latter, said connecting means extending only above the portions of said side flaps lying at the side of said door, thus leaving free the space above the door.

5. A dumping car having a bottom, a plurality of uprights mounted on said bottom, two side flaps independent of each other, means establishing horizontal hinged connection of the upper edge of said side flaps with said uprights, a door in each side flap journaled vertically on and disposed between said two side flaps so as to form a continuous barrier when closed, the hinged connecting means of said flaps extending only above said flap parts thus leaving free the space above the latter.

The foregoing specification signed at 85 Essen, Germany, this 14th day of September, 1921.

GERHARD IMMAND.

Certificate of Correction.

It is hereby certified that in Letters Patent No. 1,432,755, granted October 24, 1922, upon the application of Gerhard Immand, of Essen, Germany, for an improvement in "Dumping Cars," errors appear in the printed specification requiring correction as follows: Page 1, line 52, claim 2, after the word "flaps" insert the words *suspended from their upper edge*; same page and claim, lines 54 and 55, strike out the words "suspended from their upper edge"; and that the said Letters Patent should be read with these corrections therein that the same may conform to the record of the case in the Patent Office.

Signed and sealed this 28th day of November, A. D., 1922.

[**SEAL.**]

KARL FENNING,

Acting Commissioner of Patents.
